UNITED STATES PATENT OFFICE

170,482

WIND DEFLECTOR FOR AN AUTOMOBILE

John Sinko, Oak Park, Ill., assignor to Sinko
Mfg. & Tool Co., a corporation of Illinois

Application March 4, 1953, Serial No. 23,876

Term of patent 14 years

(Cl. D14—6)

To all whom it may concern:

Be it known that I, John Sinko, a citizen of the United States, residing at Oak Park, county of Cook and State of Illinois, have invented a new, original, and ornamental Design for a Wind Deflector for an Automobile, of which the following is a specification, reference being had to the accompanying drawing, forming a part thereof, in which:

Figure 1 is a front elevational view of a wind deflector for an automobile embodying my new design;

Figure 2 is a side elevational view;

Figure 3 is a rear elevational view; and

Figure 4 is a top plan view.
The dominant features of my design reside in the portions shown in full line.

I claim:
The ornamental design for a wind deflector for an automobile, as shown and described.

JOHN SINKO.
